TIRE

Marco Maxemovich, Warren, Mich., assignor to Uniroyal
Inc., a corporation of New Jersey

Filed Sept. 28, 1966, Ser. No. 4,073

Term of patent 14 years

(Cl. D90—20)

Fig. 1.

FIG. 1 is a perspective view of a tire embodying my new design, it being understood that the full-line portion is repeated throughout the circumference of the tire, shown by means of broken lines;

FIG. 2 is an enlarged, fragmentary, elevational view of the full-line portion shown in FIG. 1;

FIG. 3 is a fragmentary sectional view taken substantially on the plane indicated by line 3—3 in FIG. 2;

FIG. 4 is an enlarged, fragmentary, plan view of the full-line portion shown in FIG. 1; and

FIG. 5 is a fragmentary sectional view taken substantially on the plane indicated by the line 5—5 in FIG. 2.

The dominant features of my design reside in those portions shown in full lines in the drawings.

I claim:

The ornamental design for a tire, substantially as shown and described.
